UNITED STATES PATENT OFFICE.

MAX GERSTENDÖRFER AND ALBERT GERSTENDÖRFER, OF NEW YORK, N. Y.

DESIGN FOR A BOTTLE-CASE.

SPECIFICATION forming part of Design No. 19,592, dated January 21, 1890.

Application filed December 16, 1889. Serial No. 333,973. Term of patent 14 years.

To all whom it may concern:

Be it known that we, MAX GERSTENDÖRFER and ALBERT GERSTENDÖRFER, both of the city, county, and State of New York, subjects 5 of the Emperor of Germany, have invented and produced a new and original Design for Bottle-Cases, of which the following is a specification.

This invention relates to a design for a 10 bottle-case, which design consists of a cylindrical body, a cylindrical cap, a dome-shaped upper part, and a handle formed of a shoulder or base next to the dome-shaped cap, a concave neck, and a button-shaped head.

15 The nature of the design is fully shown in the accompanying drawings, in which—

Figure 1 is a side view of our bottle-case, and Fig. 2 a vertical central section on the line 1 1, Fig. 1.

20 Similar letters of reference indicate corresponding parts.

A in the drawings represents the cylindrical body of our bottle-case; B, the cap of the same, which is also of cylindrical shape, 25 and dome-shaped at the upper part.

C is the handle of the cap B, which handle is composed of a base or shoulder d next to the dome-shaped upper part of the cap, a concaved neck d' , and a button-shaped head d'' .

Having thus described our design, we claim 30 as new and desire to secure by Letters Patent—

The design for a bottle-case, composed of a cylindrical body, a cylindrical cap having a dome-shaped upper part, and a handle for 35 said cap composed of a shoulder, a concaved neck above said shoulder, and a button-shaped head, substantially as shown and described.

In testimony that we claim the foregoing as 40 our invention we have signed our names in presence of two subscribing witnesses.

MAX GERSTENDÖRFER.
ALBERT GERSTENDÖRFER.
